UNITED STATES PATENT OFFICE.

WILLIAM A. FRETWELL, OF REIDSVILLE, NORTH CAROLINA.

PLOW.

SPECIFICATION forming part of Letters Patent No. 374,829, dated December 13, 1887.

Application filed September 6, 1887. Serial No. 243,944. (No model.)

To all whom it may concern:

Be it known that I, WILLIAM A. FRETWELL, of Reidsville, in the county of Rockingham and State of North Carolina, have invented certain new and useful Improvements in Plows; and I do hereby declare that the following is a full, clear, and exact description thereof, reference being had to the accompanying drawings, and to the letters of reference marked thereon, which form part of this specification, in which—

Figure 1 is a rear perspective view of my improved plow lying upon its side. Fig. 2 is a side elevation of the same, part of the plow-share being broken away. Fig. 3 shows the plow adjusted as a shovel-plow. Figs. 4 and 5 are details of various shares which can be secured to the plow-beam for converting the plow into a cultivator, &c.

This invention relates to improvements in convertible plows; and its especial object is to provide a plow with adjustable and exchangeable handles and braces, and so constructed as to be adapted for use in connection with turn-plows, shovels, cultivators, &c., which can be severally adjusted upon the foot of the plow-beam.

The invention consists in the peculiar and novel construction and arrangement of parts, hereinafter described, illustrated in the drawings, and particularly specified in the claim hereto appended.

Referring to the accompanying drawings by letters, A designates the beam of the plow, which is made of metal, preferably cast-iron, and which is curved downward and forward at its rear end, forming a foot portion, a, as shown. This foot a is flattened on its upper front surface, and is provided with two bolt-openings, B b, as shown, the lowest, B, of which is very near the end of foot a, and the upper opening, b, is formed a proper distance above opening B, as shown. These openings B b are hereinafter referred to. A short distance above opening b is formed a transverse bolt-opening, 45 through which passes a bolt, D, which secures the plow-handles to beam A, as shown.

F F designate connecting brace rods or bars, the front ends of which are secured, by a bolt, G, and nut g, to the beam A by means of a suitable opening, H, formed in said beam at the beginning of its curvature, as shown. The front ends of bars F F are provided with a

series of openings, f f, for adjusting the handles. The said bars extend rearward to and are engaged, respectively, with the opposite handles E E of the plow at points in the plane of the straight portion of beam A.

In order to strengthen handles E E and brace the same I employ the outer metal straps or plates, K K, which are placed on the outer sides of the handles E E, and extend from the bolt D to the rod I, so that in addition to bracing the same they serve as washers for the bolt D and nut d and for the bars F F on rod I.

L designates a metal casting, which is adapted to fit under the turn-plow P, as shown in the drawings, and to which the parts of the turn-plow are secured, as shown.

The casting L is provided in its rear face with a groove or channel, l, which is provided with suitable openings at distances apart corresponding to the openings B b of the foot of the plow-beam. This foot a is adapted to fit in channel l, and the turn-plow is secured thereto by means of bolts M and nuts m, the bolts passing through suitable openings in the face of the turn-plow and in the casting and foot a, and are provided with nuts m on their inner ends, by which the turn-plow is rigidly but removably secured to the foot a of beam A, as shown.

The casting L is provided with a side depending flange, N, to which is bolted the mold-board of the plow, the rear end of the mold-board being connected by a link-bar, n, with the casting at a point just below and to one side of opening b of foot a, as shown. The front of the casting is extended and flattened to support the cutter p of the plow, as seen in Fig. 1, imparting great strength to the cutter and enabling me to widen the same in casting it, so that the turn-plow will cut a broad furrow. By connecting the brace bars F F to the ends of the brace-rod I, a substantial brace-frame is formed, which acts in connection with the plow-beam to form a plow-frame of great strength and durability.

It will be observed that by reason of the series of holes f f in the bars F F the height of the handles or their pitch in relation to the plow can be readily varied by adjusting bolt G in different openings of the bars F F.

It will be observed from the foregoing description and drawings that the turn-plow P

is attached to the beam A by two bolts only, and that by removing these bolts, which can be readily done, the turn-plow can be removed, and the shovel-plow Q, or the various shovels and blades shown in Figs. 3, 4, and 5, can be secured to the foot a instead by means of the same bolts M and nuts m, said shovels and blades being provided with suitable openings corresponding to the openings B b in foot a, so that when bolted thereon they will be in proper working position relatively to the beam of the plow.

When the shovels or cultivators are used on the beam A, it is preferable to shift the handles E E and bars F F to the positions shown in Fig. 3—that is, they are reversed—the handles E E being secured to beam A at opening H by bolt and nut G g, so that the handles lie in the same plane as the horizontal portion of beam A, while the bars F F are secured to the foot a by bolt D through opening C, as shown. The points of attachment of bars F F to handles E E, however, are unchanged.

It will be observed from the foregoing that I have a very strong adjustable and convertible plow, which has been found by practical

tests to work perfectly in any of its converted forms, either as turn-plow, shovel-plow, cultivator, &c.

It will be observed that the casting L braces 30 the turn-plow P strongly, and especially at the points which have been considered weakest in such plows, reducing the liability of breakage of plow to a minimum should the same become wedged when in use between unyielding 35 objects, as is obvious.

Having described my invention, I claim—

The combination, with the plow-beam A and handles E E, of the brace-rod I, brace-bars F F, secured at their forward end to the beam, 40 and adapted to be secured interchangeably to either of the openings C or H in the beam, and the straps K, secured to the handles, all substantially as and for the purpose set forth.

In testimony that I claim the foregoing as my 45 own I affix my signature in presence of two witnesses.

WM. A. FRETWELL.
